UNITED STATES PATENT OFFICE.

MIHRAN M. DOLMAGE, OF WASHINGTON, DISTRICT OF COLUMBIA.

WIRELESS DUPLEX SIGNALING SYSTEM.

Application filed September 17, 1920. Serial No. 410,929.

To all whom it may concern:

Be it known that I, MIHRAN M. DOLMAGE, a citizen of the United States, residing at 825 Vermont Avenue, Washington, in the 5 District of Columbia, have invented certain new and useful Improvements in a Wireless Duplex Signaling System, of which the following is a specification.

This invention relates to a system for the 10 transmission and reception of wireless signals.

This invention utilizes for this purpose voice operated circuit changing means which control the circuits of the two-way 15 wireless system in such a way as to completely eliminate the reaction of the transmitted energy upon the receiving apparatus at the transmitting station. Circuit changing means, voice controlled in their operation have heretofore been disclosed. This 20 invention differs however from most previous inventions in that it does not require the operation of a switch for putting the transmitting apparatus into electrical connection 25 with the antenna. In the system described herein, the transmitting apparatus as well as the receiving apparatus at the wireless station are normally connected to the antenna. No part of a sentence spoken into 30 the transmitter at the wireless station is distorted or lost during the time interval required for establishing a condition for proper transmission, as in the systems previously disclosed by other inventors utilizing 35 normally open transmitting circuits in combination with voice controlled means for closing the transmitting circuits to the antenna.

In radio telephony it has been customary 40 to supply to the antenna a wave of constant frequency and constant amplitude by means of a sending generator. The amplitude of this wave is then modulated in accordance with the signal to be sent.

It is well known that when a constant 45 amplitude wave of frequency C (carrier wave) is modulated by means of another constant amplitude wave of low frequency S (signal wave), the resultant modulated 50 wave can be considered to be made up of waves of constant amplitudes and of frequencies (S), (C), (C+S) and (C-S).

In Patent No. 1,414,629 I disclosed a system 55 wherein the modulated wave comprising the waves of the frequencies (C+S), (C-S) and (C) is impressed upon the grid

circuits of a detector in an auxiliary circuit tuned to radio frequency currents producing in the plate circuit of this detector waves of the signal frequency through the interaction of the waves (C+S), (C-S), (C). The result of such interaction, as well known, is the production in the plate circuit of the modulating tube waves of the frequencies (S) (2C-S), (2C+S), (C+S), 60 (C), C-S). The wave of signal frequency (S) thus obtained is then used to secure the operation of a suitably designed control relay, responsive to currents of frequency (S). In the present invention a system is used to 70 achieve the same purpose in a different way, which avoids the need for a detecting tube as hereinabove described, by separating through properly tuned circuits, the waves (S), (C+S), (C) and (C-S), produced 75 by the modulating action of the signal wave (S) upon carrier wave (C), into two groups. The first group, consisting of a signal wave (S) is used to operate the circuit changing means and a second group 80 consisting of the waves (C+S), (C), (C-S) is allowed to be radiated by the antenna. The control relay, in the present invention, remains unoperated, when no modulating signal wave is present, as all 85 currents of carrier frequency have been filtered out.

An important advantage of the system described herein consists in the possibility it affords to independently tune the antenna 90 circuit to carrier frequencies and the auxiliary circuit to signal frequencies without any reaction between the two circuits.

A further important advantage of the system described herein consists in the complete shielding of the circuit changing means itself from the interference of other wireless stations, static impulses or grinders. It is obvious that false operations would 95 result if no provision was made for such 100 shielding.

In the invention herein disclosed the voice operated relay which controls the reception of signals is connected to points of the same potential under all conditions, for 105 all waves received by the antenna whether interfering or useful in character. The system herein disclosed has been thereby made completely free from all false operations of the control relay.

The system described herein is illustrated 110 in the accompanying drawings in which

Figure 1 indicates the general method of carrying out the invention. Figure 2 indicates a modification of detail in the arrangement shown in Figure 1, this modification including the insertion of an amplifier for purposes of more certain control. In Figure 3 is shown a further modification of detail,—the means required to enable the use of a direct current control relay instead of an alternating current control relay. Figure 4 is a still further modification, also of detail, which may be used in conjunction with any of the arrangements shown on Figures 1, 2 or 3, consisting of a more efficient filter for the elimination of radio frequency currents.

This invention is illustrated in its fundamental features in Figure 1. Referring to this figure, 1 is an antenna for the transmission and the reception of signals. Antenna 1 includes two parallel branches which are also in series with the primary of receiving transformer 19. One branch includes primary winding of transformer coil 2, of controlling circuit A and secondary winding of transformer 6. The other branch includes primary winding of transformer coil 3, of automatic controlling circuit A and an artificial line comprising inductive resistance 4, and condenser 5. It is contemplated to have the artificial line balance very accurately the transmitting circuit of the duplex system. This arrangement neutralizes completely the electromotive forces generated in the secondary windings of coils 2 and 3, on all received signals. Transformer 6 is connected to the plate circuit of a vacuum tube modulator 7. The grid circuit of the same tube 7 is connected to condenser 8 which in turn is bridged by modulating transformer 9 and output winding of transformer 11. The primary winding of transformer 11 is connected to suitable source 12 of carrier currents. The secondary windings of coils 2 and 3 are closed through variable condenser 13 and inductance 14. The capacity of condenser 13 is so adjusted as to result in a resonance condition for the signal waves as described subsequently in greater detail in these specifications. Bridged around condenser 13 is control relay 18.

In Figure 2, an amplifier 15 is introduced between relay 18 and variable condenser 13 of Fig. 1, to secure a more certain operation of relay 18, in case the relay available for use as control relay is not sufficiently sensitive. In Fig. 2 the grid circuit of amplifier 15 is bridged around variable condenser 13. The plate circuit of the amplifier is closed through a resistance 16. Bridged around this resistance is the series combination of condenser 17 and relay 18. Condenser 17 is adjusted so as to secure resonance conditions for currents of signal frequency. In

Fig. 3, is shown an alternative arrangement to that shown on Fig. 2. In this figure the grid circuit of a vacuum tube 15 is again bridged around condenser 13. The plate circuit of this tube is closed through direct current relay 29, which is bridged by condenser 28 to allow the flow of alternating currents in the plate circuit. To prevent relay 29 from being continuously operated by the plate current a direct current counter electromotive force is applied through variable resistance 30 across the windings of relay 29. In this arrangement the potential of the grid battery of the vacuum tube 15 is adjusted so as to have this tube act as a detector. When alternating currents of signal frequency are impressed upon the grid circuit of vacuum tube 15 the increase in plate current results in the operation of control relay 28. Variable resistance 30 is normally so adjusted that when no modulating signal waves are present relay 29 remains unoperative.

In Fig. 4 is shown an improved arrangement over that shown in Fig. 1, as regards the effective tuning out of carrier frequency currents from the circuit of condenser 13. In this figure the circuit of the secondary windings of coils 2 and 3 is closed through anti-resonant device 31 and series resonant combination 32. Around combination 32 is bridged a second anti-resonant device 33 and variable condenser 13. Both elements 31 and 33 are anti-resonant to carrier frequency (C) and very approximately anti-resonant to carrier frequencies (C-S) and (C+S), while element 32 is resonant to carrier frequency (C) and very approximately resonant to carrier frequency (C-S) and (C+S). Variable condenser 13 is adjusted as in Fig. 1, to secure resonant conditions for currents of signal frequency (S). It will be readily understood that the combination of elements 31, 32, and 33 is essentially a filter for carrier frequency waves which prevents these waves from reaching condenser 13. Referring to the circuit shown on Fig. 1, the following operation would obtain. Carrier frequency currents generated by source 12 are amplified by modulating tube 7 and transmitted through transformer 6 and coil 2 to the antenna. These carrier frequency currents include the waves (C+S), (C) and (C-S). The combination of condenser 13 and inductance 14 is so chosen as to offer a very high impedance to the above carrier frequency currents, but a low impedance to current of signal frequency. Relay 18 is also chosen with a sufficiently large inductance so as to offer a high impedance to currents of carrier frequency.

In the absence of modulating signal waves relay 18 remains unoperated. When however currents of signal frequency are im-

pressed upon the grid circuit of tube 7, these currents, amplified by tube 7, flow through transformer 6, primary windings of coils 2 and 3 and balancing impedance having elements 4 and 5. The secondaries of coils 2 and 3 are so connected that the electromotive forces induced are cumulative. Since, in addition, the condenser 13 and inductance 14 forms a resonant combination to currents of signal frequency such currents will flow freely in the auxiliary circuit and operate relay 18. When operated, this relay short circuits tuning condenser 23, thereby preventing any of the transmitted modulated waves (C), (C+S), (C-S) from producing audible signals in receiver 27. This receiver remains, therefore, absolutely silent.

However, on signals received by the antenna, on account of the electrical association of coils 2 and 3, in the manner shown and as previously described, the two terminals of condenser 13 will be at the same potential. This result follows, since by construction, on received signals the electrical impedance 25 of artificial balancing circuit, comprising elements 3, 4 and 5, is equal to the impedances of the transmitting circuit comprising elements 2 and 6. The electromotive forces generated in the secondaries of coils 2 and 30 3 will consequently be equal and opposite in phase. Hence, no current flows in the circuit of secondaries of coils 2 and 3, on received signals, whether such received signals be due to carrier frequency waves from 35 other transmitted stations, static impulses or grinders. No current can therefore flow through relay 18. This relay remains in its non-operated position on all signals received by the antenna. The carrier frequency currents flowing through transformer 19 on received signals will therefore reach their destination unhampered and the receiving will be obtained in full amplitude at receiver 27. The modification shown on Fig. 2 is merely 40 for the purpose of securing increased certainty of operation as already described, when large currents are required to operate control relay 18. Further modification shown on Fig. 3, furnishes a rather convenient means for using a direct current relay 45 instead of an alternating current relay. With this arrangement the tuning of the auxiliary circuit need not be very close since the effect of the increase in plate current, due to carrier frequency waves, can be 50 eliminated to any degree desired by the regulation of the counter electromotive battery through the variation of adjustable resistance 30. The improved arrangement 55 shown on Fig. 4 can be used in combination with any one of the arrangements shown on Fig. 1, Fig. 2 or Fig. 3. It may not, at first sight, be immediately clear that it is possible to tune the auxiliary circuit A of the 60 present invention to currents of signal fre-

quency without prejudice to the flow of currents of carrier frequency into the antenna or without disturbing the antenna resonance conditions if the antenna circuit has already been tuned to currents of carrier 70 frequency. This result is a typical consequence of the special arrangement indicated on the drawings of this invention and may be demonstrated very clearly as shown hereunder. Referring to Fig. 1 of the drawings 75 and calling—

E =Electromotive force of the transmitted waves acting through the back impedance of the transmitting equipment.

Z_4 =Impedance of the transmitting equipment. 80

It will be remembered in this connection that elements 4 and 5 balance exactly the transmitting equipment, as brought out on page 3 of the specifications, lines 17 to 19, 85 and therefore have the same total impedance.

Z_3 =Impedance of the secondary windings of coils 2 and 3.

Z_2 =Impedance of the primary windings of coils 2 and 3 which are directly in series with elements 4, 5, and 6.

Z_1 =Impedance of the antenna circuit, including that of element 19 with associated 95 receiving equipment closed through.

Z =Impedance of condenser 13.

PM =Mutual impedance of primary and secondary windings of coils 2 and 3 for

frequency $\frac{P}{2\pi}$. 100

I_1 =Current in antenna circuit.

I_3 =Current in auxiliary circuit.

I_4 =Current in balancing elements 4 and 5.

$I_1 + I_4$ =Total current flowing through element 6. 105

We may write the three following equations:—

(1) The equation covering the transmitting equipment and the antenna circuit— 110

$$E = Z_4(I_1 + I_4) - PMI_3 + Z_1I_1$$

(2) The equation covering the antenna circuit and the balancing equipment. 115

$$0 = Z_1I_1 - PMI_3 - (Z_2 + Z_4)I_4$$

(3) The equation covering the closed auxiliary circuit—

$$0 = PM(I_1 + I_4) + PMI_4 - (2Z_3 + Z)I_3 120$$

Combining in the above equations all similar terms containing the same currents and solving for I_1 and I_3 , we get—

$$(4) I_1 = \frac{E}{(Z_2 + Z_4) + 2Z_1} 125$$

$$(5) I_3 = \frac{E(PM)}{2[(Z_2 + Z_4)(Z + Z_3) - P^2M^2]}$$

Considering first the expression for the 130

antenna current it is clear that it depends upon the three impedances Z_2 , Z_4 and Z_1 but in no way upon Z or Z_3 . The antenna circuit may therefore be tuned in the usual way 5 for resonance to carrier frequency currents, independently of the value of Z .

Considering next the expression for the current in the auxiliary circuit it will be noted that it depends upon the five impedances PM , Z_2 , Z_4 , Z_3 , and Z . It will also be noted that this current does not depend upon Z_1 , the impedance of the antenna circuit. The impedance Z of condenser 13 may therefore be chosen so as to secure maximum current 10 conditions for the audio frequency components of the electromotive force E , without in any manner interfering with the securing of resonance conditions in the antenna for radio frequency currents.

20 It is clear from the above description that this invention is not in any way limited to any one particular type of wireless signaling system. What is characteristic of the system is the use of an auxiliary circuit tuned 25 to currents of signal frequency, an antenna circuit tuned to carrier frequency, of a control relay in this auxiliary circuit actuated by currents of signal frequency, with balancing artificial network, substantially as described. Instead of using a control relay of 30 alternating current type, I find it desirable in some cases, to use a direct current relay in association with a counterbalancing electromotive force, this combination taking the place 35 of the alternating current relay 18 and condenser 17.

What I claim is:—

1. In a system for the transmission and 40 reception of wireless signals, transmitting apparatus normally connected to the antenna receiving apparatus normally connected to the antenna, an auxiliary circuit tuned to currents of signal frequency, a control relay in said circuit and circuit changing means 45 under the control of aforesaid relay rendering inoperative the receiving apparatus when said system is used for transmission.

2. In a system for the transmission and 50 reception of wireless signals, an antenna, transmitting apparatus normally connected to said antenna, an auxiliary circuit tuned to currents of signal frequency, a second circuit balancing the transmitting circuit on received signals, a control relay in said auxiliary circuit and means under the control of aforesaid relay rendering the receiving circuit inoperative when said system is used for transmission.

3. In a system for the transmission and 60 reception of wireless signals, an antenna, transmitting apparatus normally connected

to the antenna, an auxiliary circuit tuned to currents of signal frequency, a second circuit balancing the transmitting circuit on received signals, means for connecting said auxiliary circuit with said transmitting circuit and said balancing circuit, a control relay connected to points of equal potential for received energy in aforesaid auxiliary circuit, receiving apparatus normally connected to the antenna, and means under the control of aforesaid relay rendering inoperative the receiving apparatus when said system is used for transmission. 65

4. In a system for the transmission and 70 reception of wireless signals, the combination of an antenna, transmitting apparatus, and an auxiliary circuit—these elements wired in a bridge arrangement with the antenna and auxiliary circuit occupying opposite arms of the bridge, with voice controlled circuit changing means in said auxiliary circuit completely shielded from all interfering waves received through the antenna. 75

5. In a system for the transmission and 80 reception of wireless signals, a modulating device, the bridge combination of an antenna, transmitting apparatus and an auxiliary circuit, the antenna and the auxiliary occupying opposite arms of said bridge, receiving apparatus, and circuit changing means controlled by signaling currents rendering inoperative the receiving apparatus when said system is used for transmission. 85

6. In a system for the transmission and 90 reception of wireless signals, an antenna, transmitting apparatus, receiving apparatus, an auxiliary circuit, means for filtering out currents of carrier frequency from said auxiliary circuit, a control relay in said circuit and means under the control of said relay rendering inoperative the receiving apparatus when said system is used for transmission. 95

7. In a system for the transmission and 100 reception of wireless signals, the combination of an antenna, transmitting apparatus and an auxiliary circuit in bridge arrangement, a control relay connected to points of equal potential for received signals in said bridge, means for preventing the flow of transmitted carrier currents through said relay, and means under the control of said relay rendering inoperative the receiving apparatus when said system is used for transmission. 105

In testimony whereof I affix my signature.

MIHRAN M. DOLMAGE.
